UNITED STATES PATENT OFFICE.

CLARENCE B. R. BITTER, OF TOLEDO, OHIO.

DESIGN FOR A PUZZLE-BOX.

SPECIFICATION forming part of Design No. 26,162, dated October 6, 1896.

Application filed August 7, 1896. Serial No. 602,089. Term of patent 3½ years.

To all whom it may concern:

Be it known that I, CLARENCE B. R. BITTER, a citizen of the United States, residing at Toledo, in the county of Lucas and State of Ohio, have invented and produced a new and original Design for Puzzle Boxes or Cases, of which the following is a specification, reference being had to the accompanying drawings, which form a part thereof, in which—

10 Figure 1 is a plan view of a puzzle box or case showing my design, and Fig. 2 a longitudinal section thereof on the line 2 2, these two views being deemed necessary in order to fully illustrate my design.

15 The leading feature of my new and original design for puzzle boxes or cases consists of an oblong bottom plate or board 5, which is straight at one end and semicircular at the other, as shown at 7, and the sides thereof are 20 parallel, and said bottom plate or board is provided with a vertical wall or flange 8, which is formed thereon at a short distance from the edge thereof, and which is of the same form as the bottom plate or board, being straight at one end, as shown at 9, and 25 semicircular at the other, as shown at 10, and I also provide a circular vertical wall or flange 11, which connects with the transverse end portion 9 of the vertical wall or flange 8, centrally thereof, and with the sides of said vertical wall or flange 8, at 13, and by means of these vertical walls or flanges 8 and 12 an oblong elliptical space 14 is formed, the side portions of which are parallel and the ends 30 semicircular.

Within the walls or flanges 8 and 9 is a similar wall or flange 15, which forms the inner boundary of the space 14, the ends thereof being circular and the sides parallel, and 40 whereby a space 16, similar to the space 14, is formed, the ends of which are circular and the sides parallel, and connected with the wall

15, near the straight end of the box or casing and at one side thereof, is a spiral vertical wall or flange 17, the end of which terminates 45 at 18, and by which an oblong central space or chamber 19 is formed.

Although I have referred to the wall or flange 17 as spiral, the coils thereof are oblong in form, and the space 20 between the 50 same is similar to the spaces 14 and 16, though not quite so wide. By means of the vertical wall or flange 12 corner compartments or spaces 21 are formed, which are triangular in form, and which communicate 55 with the space 14 by means of passages or openings 22, formed in said wall or flange, and the wall or flange 15 is also provided with similar openings or passages 22 at each end thereof and in one side, and the wall or flange 60 17 is provided with an opening or passage 22 at one end thereof and also in one of the coils thereof in line with the longitudinal center of the box or case.

The entire design is symmetrical in form, 65 and the chambers formed by the various vertical walls or flanges are all similar in form, with the exception of the corner chambers 21, which are triangular in form, and the device is thus made to appear regular and symmetrical to the eye.

Having fully described my new and original design, I claim as new and desire to secure by Letters Patent—

The design for a puzzle box or case herein 75 shown and described.

In testimony that I claim the foregoing as my invention I have signed my name, in presence of the subscribing witnesses, this 3d day of August, 1896.

CLARENCE B. R. BITTER.
